CURLER SPINDLE FOR HAIR WAVERS

Otto A. Langos, Chicago, Ill., assignor to Bernard A. Sterling, Chicago, Ill.; Sara Sterling executrix of said Bernard A. Sterling, deceased

Application July 12, 1941, Serial No. 402,076

8 Claims. (Cl. 132—33)

This invention relates to a curler spindle for hair wavers.

More particularly, the present invention has to do with a curler spindle for hair wavers of the type in which the waver comprises a protector clamp and a curler spindle, the protector clamp being applied to the lock of hair close to the scalp and the hair being wound upon the spindle which is then usually mounted on the protector clamp and turned to tension the hair, whereupon a pad and heater are applied for purposes well understood in the art.

Heretofore, these curler spindles have usually been made of light weight metal which permitted them to be formed solid without undue weight upon the head. The light weight metal suitable for making curler spindles of this sort is not now readily available due to war priorities.

One of the main objects of the present invention is to provide a curler spindle of simple, relatively inexpensive and improved construction, and, more particularly, a curler spindle formed of sheet metal shaped to tubular form to make the spindle light in weight, and an improved curler spindle of the character set forth having end members formed to strengthen the spindle against collapse and secured to the ends of the spindle in a manner to accomplish the desired results.

Another and more specific object of the invention is to provide an improved form of tubular curler spindle which is not only light in weight and relatively strong, but which is provided with improved journal portions for journaling the spindle for rotation upon the protector clamp; also, in conjunction with a curler spindle of the improved form set forth, an improved form of ratchet for cooperation with the usual or any suitable form of pawl to prevent unwinding of the hair from the spindle, and an improved form of finger piece for turning the spindle after it is applied to the clamp.

Further objects and advantages of the invention will appear from the following detailed description, taken in connection with the accompanying drawings in which:

Figure 1 is an elevational view of a curler spindle embodying the present invention, and showing the same applied to a protector clamp;

Figure 2 is an elevational view of the curler spindle alone and taken at substantially right angles to Figure 1;

Figure 3 is an exploded view showing the parts of the spindle;

Figure 4 shows the form of the sheet metal

blank from which the body part proper of the spindle is formed;

Figure 5 shows more or less diagrammatically one illustrative method of forming the spindle proper from the blank shown in Figure 4;

Figure 6 shows the blank from which is formed the cup-shaped shell or ferrule for one end of the curler spindle;

Figure 7 is an inner end view of the cup-shaped shell after forming the same to cup-shaped form;

Figure 8 shows the step of forming the ratchet teeth in the cup-shaped shell shown in Figure 7;

Figure 9 shows the blank from which is formed the cup-shaped shell or ferrule for the opposite end of the spindle;

Figure 10 is an inner end view of the cup-shaped shell formed from the blank shown in Figure 9 and after forming the same to cup-shaped form;

Figure 11 is a sectional view taken on the line 11—11 of Figure 10;

Figure 12 is a view showing fragmentarily the tubular stock from which the finger pieces are formed;

Figure 13 shows the step of forming the finger piece or handle for turning the curler spindle;

Figure 14 is a longitudinal section through the completed curler spindle; and

Figure 15 is a view similar to Figure 2 showing a modified form of curler spindle embodying the present invention.

Referring now in detail to the drawings, the hair waver selected for illustration comprises a protector clamp 10 and a curler spindle 11.

The protector clamp 10 may comprise pivoted jaws adapted to be clamped to the lock of hair close to the scalp, as well understood in the art. The protector clamp 10 is shown as having upturned supports 12 and 13 to receive and support the curler spindle 11 with the hair wound thereon and in such manner that the spindle 11 may be turned to tension the hair, also as well understood in the art. A spring pawl 14 on the protector clamp cooperates with a ratchet on the curler spindle 11 to prevent retrograde movement or unwinding of the spindle 11.

The curler spindle 11 to which the present invention is directed is formed of flat sheet metal stock of suitable gauge which is blanked out to the form shown at 11a in Figure 4. The blank 11a is placed, for example, upon a mandrel 18 shaped externally to conform with the internal form of the finished tubular spindle 11. The blank 11a is then folded or closed around the mandrel 18

with the opposite edges 19 of the blank (Figure 4) brought into abutting engagement at 20 (Figure 5). A holder member 21 may be provided for holding the blank 11a in place during the forming operation. For the purpose of closing the blank 11a around the mandrel 18 I have shown rollers 22, but this may vary widely within the scope of the present invention. It is to be understood, for example, that the blank 11a may be folded first to generally U-shaped form in cross section and then closed to complete the formation of the tubular spindle.

The resulting curler spindle is of hollow or tubular form having cylindrical ends 24 and 25 and of circular cross section, diminishing in diameter from the opposite cylindrical ends to the intermediate portion of the spindle centrally between its opposite ends. The mandrel 18 may be divided between its ends to permit the opposite ends of the mandrel to be pulled out endwise upon completion of the spindle forming operation, or the mandrel may be of any other character adapted to be removed from the spindle.

The cup-shaped shell 26 at one end of the spindle 11 is drawn or otherwise brought to cup-shaped form from a circular sheet metal blank 26a. The end wall 27 of the shell 26 is preferably pressed inwardly to fit within the interior of the adjacent end of the tubular spindle 11 (as shown in Figure 14) thereby holding the tubular spindle against collapse at one end. An opening 28 is punched in the end wall 27 centrally thereof. The opening 28 is shown of generally circular form, but it may be of rectangular or other suitable non-circular form similar to the opening in the cup-shaped shell at the opposite end of the spindle 11 as will presently appear.

External ratchet teeth 30 are formed in the cup-shaped shell 26 for engagement with the pawl 14 on the protector clamp. These ratchet teeth may be formed, for example, by forcing the cup-shaped shell 26 through a die 32 by means of a punch 34. The die 32 has internal teeth 33 for forming the desired external ratchet teeth 30 on the shell 26, and the punch 34 has external teeth 35 corresponding with the internal teeth 33 within the die 32 with the thickness of the metal shell 26 between the teeth. The shell 26 may be held in place on the upper ends of the teeth 33 (as shown in Figure 8) until the punch 34 enters the shell 26 and forces the same through the die 32, but this may be varied within the scope of the present invention. By the method disclosed the shell 26 is ejected from the die 32 by the ratchet tooth forming movement of the punch 34 which operates to force the shell through the die from one end to form the teeth on the shell and to force the shell with the teeth thereon out from the opposite end of the die.

The cup-shaped shell 40 for the opposite end of the spindle 11 is similarly drawn or brought to cup-shaped form from a circular metal blank 40a. The end wall 41 of the shell 40, like the end wall 27 of the shell 26, is preferably pressed inwardly to fit within the interior of the adjacent end of the tubular spindle to hold this end of the spindle against collapse. An opening 42, preferably of rectangular or other suitable non-circular form, for a purpose which will presently appear, is punched in the end wall 41 centrally thereof. A pin 45 is riveted at 46 in the opening 28 in the end of the shell 26. This pin 45 has 70 turning movement in the support 12 when the curler spindle 11 is mounted on the protector

clamp. The inner end of a second pin 47 is pressed into the square, rectangular, or other non-circular opening 42 in the end of the shell 40. In pressing the pin 47 into the opening 42 the pin takes the shape of the opening, thereby effectively fixing the pin to the shell 40 and against turning movement relative to the shell. The inner end of the pin 47 is shown as riveted over at 48. When the curler spindle is mounted on the protector clamp, the pin 47 has turning movement in the support 13.

The shells 26 and 40 are pressed into place upon the opposite cylindrical ends 24 and 25 of the curler spindle 11, the pressed fit of the shells on the ends of the curler spindle being of a character to fix the shells securely in place and prevent turning movement of the same on the ends of the spindle. The shell 26 having the ratchet teeth 30 for cooperation with the pawl 14 is more subject to becoming loose on the spindle 11 than is the shell 40 at the opposite end of the spindle. If the shell 26 does become loose on the spindle, the pawl 14 will fail to prevent unwinding of the spindle. Therefore, in pressing the shell 26 into place on the spindle 11, I preferably force the inner end of the annular wall of the shell inwardly so that it and the inner ends of the ratchet teeth 30 actually bite at 50 (Figure 14) into the tubular wall of the spindle. This very effectively fixes the shell 26 against turning movement relative to the spindle 11. If desired, the inner end of the annular wall of the shell 40 at the opposite end of the spindle may be similarly forced inwardly so that it will actually bite into the tubular wall of the spindle to preclude relative turning movement between this shell and the spindle.

The saddle-like retainer 52 has at one end projecting tongues 53 which are pivoted on the shell 40, for example by means of a cross pin 54, the ends of which may be riveted over to prevent displacement of the pin after it is applied through the registering openings in the tongues 53 and the adjacent end of the spindle. The retainer 52 is usually curved to conform with the periphery of the spindle and is adapted to be swung away from the spindle for introduction of the strands or lock of hair between the spindle and the retainer, which is then closed to grip the hair between the spindle and the retainer, as well understood in the art.

The handle 56 for turning the spindle to wind the hair thereon is preferably formed of thin metallic tubular stock indicated fragmentarily, for example, at 56a in Figure 12. Upon first cutting this stock to form an endless ring shown at 56b in Figure 13 of the desired length, this ring is placed, for example, between a pair of forming dies 58, 59, and preferably with a pin 60 corresponding with the pin 47 concentrically within the ring 56b as shown more or less diagrammatically in Figure 13. The forming dies 58, 59 are then closed to bring the annular ring 56b to the form of the handle 56 as shown in Figure 3. Before completing the flattening of the flattened portions of the handle 56, the pin 60 is preferably withdrawn to permit the flattened portions of the handle to be pressed tightly together. The intermediate hub part 62 of the handle is then pressed onto the pin 47 and may be spot-welded at 63 (Figure 14) or otherwise fixed securely against turning movement relatively to the pin 47.

The resulting curler spindle which is now ready for use in the usual manner is of relatively great strength, particularly against collapse which

otherwise might result due to its tubular form. The spindle is of light weight notwithstanding the fact that the lighter weight metals are not readily available due to war priorities, and the improved construction set forth permits employment of sheet stock with the advantages set out.

The embodiment of the invention illustrated in Figure 15 is the same as the other embodiment except that in Figure 15 the ratchet teeth 30' are formed in the shell 40' at the handle end of the spindle. This may be accomplished by lengthening the shell 40' to provide for the teeth 30' and at the same time permitting pivoting of the retainer 52' to the shell 40' by the pin 54'. In this case the shell 26' at the opposite end of the spindle conforms in general with the shell as shown at 40 in the previous embodiment of the invention.

I do not intend to be limited to the precise details shown or described.

I claim:

1. As a new article of manufacture, a curler spindle formed of sheet metal stock shaped to tubular form with its opposite ends substantially cylindrical and diminishing in diameter from said cylindrical ends to the intermediate portion of the spindle centrally between its opposite ends and with the opposite longitudinal edges of the sheet metal stock in abutting engagement, and cup-shaped shells formed of sheet metal stock and fixed telescopically over the opposite substantially cylindrical ends of the spindle, said cup-shaped shells having end walls pressed inwardly to fit within the ends of the spindle to hold the same against collapse.

2. As a new article of manufacture, a curler spindle formed of sheet metal stock shaped to tubular form with its opposite ends substantially cylindrical and diminishing in diameter from said cylindrical ends to the intermediate portion of the spindle centrally between its opposite ends and with the opposite longitudinal edges of the sheet metal stock in abutting engagement, cup-shaped shells formed of sheet metal stock and fixed telescopically over the opposite substantially cylindrical ends of the spindle, said cup-shaped shells having end walls pressed inwardly to fit within the ends of the spindle to hold the same against collapse, and ratchet teeth pressed into the annular wall of one of said shells.

3. As a new article of manufacture, a curler spindle formed of sheet metal stock shaped to tubular form with its opposite ends substantially cylindrical and diminishing in diameter from said cylindrical ends to the intermediate portion of the spindle centrally between its opposite ends and with the opposite longitudinal edges of the sheet metal stock in abutting engagement, cup-shaped shells formed of sheet metal stock and fixed telescopically over the opposite substantially cylindrical ends of the spindle, said cup-shaped shells having end walls pressed inwardly to fit within the ends of the spindle to hold the same against collapse, and ratchet teeth pressed into the annular wall of one said shell, the inner end of the annular wall of said last mentioned shell being pressed inwardly to bring the inner end of the shell and the ratchet teeth thereon into biting engagement with the adjacent wall of the spindle.

4. As a new article of manufacture, a curler spindle formed of sheet metal stock shaped to tubular form with its opposite ends substantially cylindrical and diminishing in diameter from said cylindrical ends to the intermediate portion of the spindle centrally between its opposite ends and with the opposite longitudinal edges of the

sheet metal stock in abutting engagement, cup-shaped shells formed of sheet metal stock and fixed telescopically over the opposite substantially cylindrical ends of the spindle, said cup-shaped shells having end walls pressed inwardly to fit within the ends of the spindle to hold the same against collapse, ratchet teeth pressed into the annular wall of one of said shells, and coaxial pins fixed in the end walls of said shells for journaling said spindle for turning movement on a protector clamp.

5. As a new article of manufacture, a curler spindle formed of sheet metal stock shaped to tubular form with its opposite ends substantially cylindrical and diminishing in diameter from said cylindrical ends to the intermediate portion of the spindle centrally between its opposite ends and with the opposite longitudinal edges of the sheet metal stock in abutting engagement, cup-shaped shells formed of sheet metal stock and fixed telescopically over the opposite substantially cylindrical ends of the spindle, said cup-shaped shells having end walls pressed inwardly to fit within the ends of the spindle to hold the same against collapse, ratchet teeth pressed into the annular wall of one of said shells, coaxial pins fixed in the end walls of said shells for journaling said spindle for turning movement on a protector clamp, and a handle pressed from a substantially circular ring to form an intermediate hub part fixed on one of said pins and with the sides of the ring flattened together on opposite sides of said hub part.

6. As a new article of manufacture, a curler spindle formed of sheet metal stock shaped to tubular form with its opposite ends substantially cylindrical and diminishing in diameter from said cylindrical ends to the intermediate portion of the spindle centrally between its opposite ends and with the opposite longitudinal edges of the sheet metal stock in abutting engagement, cup-shaped shells formed of sheet metal stock and fixed telescopically over the opposite substantially cylindrical ends of the spindle, said cup-shaped shells having end walls pressed inwardly to fit within the ends of the spindle to hold the same against collapse, ratchet teeth pressed into the annular wall of one of said shells, coaxial pins fixed in the end walls of said shells for journaling said spindle for turning movement on a protector clamp, and a handle pressed from a substantially circular ring to form an intermediate hub part fixed on one of said pins and with the sides of the ring flattened together on opposite sides of said hub part, the pin to which said handle is secured being pressed into a generally polygonal opening in the end wall of one of said shells to fix said pin against turning movement relative to said shell.

7. The method of forming a curler spindle of the class described which comprises shaping a flat metal blank to tubular form with the opposite ends substantially cylindrical and diminishing in diameter from said cylindrical ends to the intermediate portion of the spindle centrally between its opposite ends and with the opposite longitudinal edges of the sheet metal stock in abutting engagement, shaping flat sheet metal blanks to the form of cup-shaped shells, pressing ratchet teeth in one of said shells, fixing pins in the end walls of said shells in coaxial relation, fixing said shells telescopically over the substantially cylindrical ends of the spindle, pressing a handle to shape from a substantially circular ring to form an intermediate hub part with the sides of the

ring flattened together on opposite sides of said hub part, and applying the handle to one of said pins by placing the hub part thereof over the pin and fixing said hub part of the handle to said pin.

8. As a new article of manufacture, a curler spindle formed of sheet metal stock shaped to tubular form, cup-shaped shells formed of sheet

metal stock and fixed telescopically over the opposite ends of said spindle, ratchet teeth pressed into the annular wall of one of said shells, coaxial pins fixed in the end walls of said shells, and a handle fixed on one of said pins.

OTTO A. LANGOS.
